UNITED STATES PATENT OFFICE.

JAMES W. HUGHES, OF PHILADELPHIA, PENNSYLVANIA.

COIN-CONTROLLED LOCK FOR VENDING DEVICES.

Original application filed October 23, 1917, Serial No. 198,028. Patent No. 1,395,676. Divided and this application filed October 13, 1921. Serial No. 507,585.

To all whom it may concern:

Be it known that I, JAMES W. HUGHES, a citizen of the United States, and resident of Philadelphia, county of Philadelphia and

5 State of Pennsylvania, have invented an Improvement in Coin-Controlled Locks for Vending Devices, of which the following is a specification.

This invention has for its object the construction of a coin-controlled lock adapted for a vending device wherein one or a plurality of coins may be required to put it into action to unlock the device for permitting access to the article to be vended.

10 15 A further object of my invention is to provide, for an automatic vending device, a coin-controlled lock having adjusting means which make it possible to readily change the number of coins necessary to be deposited to insure operation, whereby the lock may be set to operate by the deposit of one or more coins to suit the price of the article being vended.

20 25 With the above and other objects in view, the nature of which will be more fully understood from the description hereinafter, the invention consists in the novel construction of coin-controlled lock for vending devices, as hereinafter more fully described and defined in the claims.

25 30 Referring to the drawings: Fig. 1 is a vertical section taken on line 1—1 of Fig. 2, illustrating the general construction of my improved coin-controlled lock, and also having the electric circuits controlled by the coins shown in diagrammatic form; Fig. 2 is a vertical section taken on line 2—2 of Fig. 1 and with the electrical means for releasing the coins diagrammatically illustrated; and Fig. 3 is a transverse section of my improved coin-controlled lock taken on line 3—3 of Fig. 1.

35 40 The vending device may be of any suitable construction and for this reason no specific description of it is shown. A suitable type of vending device, with which my improved coin-controlled lock may be used, is set out in Letters Patent Number 1,395,676, dated November 1, 1921, and issued upon an application Serial Number 198,028, and filed October 23, 1917, of which this application is a division, but my improved coin-controlled lock may be employed not only with a vending machine of the character there shown, but may be combined with any machine or

apparatus which is required to be put into operation by the deposition of one or more coins in a coin-controlled locking device.

The coin-controlled electrically operated lock releasing means consists of battery or other source of electric potential 16 which operates an electro-magnet 17 through a circuit comprised of wires 21^a and 22^a the coin supporting armature 12, plug switch 19, the metal pins 4, 5, 6 and 7, as the case may be, wire 20^a and the metal coins 21 themselves. It will be noted that the plug switch 19 has a plurality of segments 4^a, 5^a, 6^a and 7^a, respectively connected to the metal pins 4, 5, 6 and 7. The object of this is to provide a means, whereby a varying predetermined number of coins will be required to close the electric circuit before the vending means will be released. For instance, with the plug 19^a inserted at 7^a, one coin will be required, at 6^a two coins, at 4^a three coins, and at 5^a four coins. If coins of smaller diameter than the required denomination be inserted in the coin slot 14, they will roll through and out from the openings 8, 9, 10 and 11, and be returned to the would-be purchaser. The metal pins 4, 5, 6 and 7 are mounted, in a block 3 of suitable insulating material, such as hard rubber which is surrounded by a metal casing 2. It will be noted that the front of the coin slot 14 is covered by glass 20 so that the inserted coins are exposed in full view when in circuit controlling position.

35 40 To release the coins, an electro-magnet 22 is provided, which, when energized, serves to attract the armature 12, pivoted at 13, against the action of the spring 23. The excitation of this magnet may be effected by the movement of the lever 27 when manually operated (to open a suitable cover for permitting filling of the case, for example), by the momentary contacting of the said lever 27 with a contact 26. This completes a circuit 25 from the source of electric potential 16 through the magnet 22.

45 50 In operation, the would-be purchaser inserts the proper coin or coins in the coin slot 14. The coins complete the electric circuit through the magnet 17 which operates the locking armature 18 to unlock reciprocable part 18^a of the vending device, as shown in Fig. 1, to permit it to be moved. The attendant receive notification in some suitable manner that the vending device is empty.

(which is not the subject of this application) and throws the lever 27 to a position where the circuit through contact 26 is closed and the coins are released by armature 12 and allowed to fall into a suitable coin receiving receptacle. When the cabinet (not shown) is refilled, the lever 27 is moved back in the direction of the arrows, placing the device in operative condition once more to be controlled by the coin-controlling means.

It will be apparent that my improved coin-controlled lock, as above described, is simple in construction, and it allows the price of the vended article to be varied without necessitating any complicated changes in the mechanism, and that further, it discourages the use of slugs or counterfeit coins because the inserted coins are carried in plain view behind the glass until released by the attendant.

It will be observed that the chute or race-way 14 through which the coins pass is formed in the insulating material 3 and does not control the circuits leading to the magnet 17 except when they rest in contact with the metal pins 4, 5, 6 and 7, and upon the inclined upper surface of the retaining armature 12; and in respect to the former, this contact is the better insured by the abutment pins 15 in the path of the coins which force them over in contact with the aforesaid contact pins 4, 5 and 6.

The inclined armature surface forces the lower coin against the contact pin 7. In this way the coins take a somewhat zig-zag path and pile upon each other, the lowermost coin resting upon the inclined surface of the retaining armature 12. When the armature is operated by the magnet 22, as before explained, all of the coins pass down the chute into the receiving receptacle (not shown). The minor details of this coin-controlling lock are capable of modification and this may be done, so long as the general principle of using the coins in stacked relation, for controlling the energizing circuit, is maintained. The simplicity of the means for changing the number of coins required to operate the magnetically operated lock, is an important feature of the invention. The obliquity of the top of the armature 12 is not only to hold the coin against the contact 7, but also to cause an undesirable coin to be projected laterally from the coin chute, as indicated in dotted lines.

It will now be apparent that I have devised a novel and useful construction which embodies the features of advantage enumerated as desirable in the statement of the invention and the above description, and while I have in the present instance shown and described the preferred embodiment thereof which is best suited to give satisfactory and reliable results in practice, it is to be under-

stood that the same is susceptible of modification in various particulars without departing from the spirit or scope of the invention or sacrificing any of its advantages.

Having now described my invention, 70 what I claim as new and desire to secure by Letters Patent, is:

1. A coin-controlled lock for a vending machine, comprising a lock, combined with a coin controlled means for operating the 75 lock consisting of a magnet to operate the lock, a source of electric energy, a coin chute having a series of contacts in its length with respect to which the several coins abut while resting in contact with each other, a general circuit including the source of energy, the magnet and the several contacts of the chute, and a plug switch device for putting one or more of the contacts into circuit and cutting off the remainder from the circuit, 80 whereby the magnet may be energized upon the deposition of one or more coins in the chute as predetermined by the plug switch.

2. The invention according to claim 1, further combined with an electro-magnetically operated means for retaining the coins in the chute, and manually operable circuit controlling means for insuring the energizing of the coin retaining means to automatically release and discharge the coins after 95 the lock has been actuated.

3. A coin-controlled lock for a vending machine, comprising a lock, combined with an electro-magnetically operated lock releasing means, a coin chute in which the coins 100 rest one upon the other in series, a retaining means for holding the coins in the chute, a plurality of circuit contacts in the chute with which the respective coins contact when positioned in the chute, a source of electrical 105 energy, a circuit including the source of energy and the electro-magnetically operated lock releasing means, adjustable means for including in the circuit one or more of the series of contacts in the chute so as to 110 require one or more coins to close the circuit as predetermined, and means for releasing the coins from the chute.

4. A coin-controlling lock for vending machine, comprising a magnet to operate the 115 lock, a source of electric energy, a main circuit including the source of energy and the magnet, a vertical coin chute of insulating material, a movable retaining means for temporarily holding the coins in the chute 120 in series relation one upon the other, contact pins in the chute arranged alternately upon the opposite sides against which the respective coins rest, separate circuits from each contact pin, and a switch device for putting either of the circuits into series with the main circuit, whereby one or more coins 125 may be required to close the circuit for operating the magnet.

5. A coin-controlled lock for vending ma- 130

- chines, comprising a magnet to operate the lock, a source of electric energy, a main circuit including the source of energy and the magnet, a vertical coin chute of insulating material having lateral openings of slightly less size than the thickness and diameter of the coins required said openings arranged alternately on opposite sides of the chute in staggered relation, a manually controlled movable retaining means for temporarily holding the coins in the chute in series relation one upon the other, contact pins in the chute arranged alternately upon opposite sides and above the lateral openings against which the respective coins rest, separate circuits from each contact pin, and a switch device for putting one or more of the said circuits in series with the main circuit, whereby one or more coins may be required to close the circuit for operating the lock 20 operating magnet.

In testimony of which invention, I hereunto set my hand.

JAMES W. HUGHES.
